UNITED STATES PATENT OFFICE.

GLENN S. NOBLE, OF CHICAGO, ILLINOIS.

MASSAGE-MACHINE.

1,322,720.

Specification of Letters Patent. Patented Nov. 25, 1919.

Application filed June 6, 1914. Serial No. 843,358.

To all whom it may concern:

Be it known that I, GLENN S. NOBLE, a citizen of the United States, residing at Chicago, in the county of Cook and State of Illinois, have invented certain new and useful Improvements in Massage-Machines, of which the following is a specification.

This invention relates to machines for giving body treatments and is particularly applicable for giving treatments to the back, shoulders, and rear portions of the arms of the person to be treated.

Among the objects of this invention are to provide an exceedingly simple and efficient machine for giving a rolling or massaging treatment; to provide means whereby the machine may be readily adjusted for different persons, and may be adapted to regulate the pressure for the comfort or convenience of the person to be treated; and in general, to provide such an improved structure and details of construction as will appear more fully in the following specification.

25 In the accompanying drawings illustrating this invention:

Figure 1 is a side view of the machine, parts being shown diagrammatically; and

30 Fig. 2 is a plan view of the same, parts being broken away for convenience in illustration.

In general, my improved machine comprises a series of rollers or massage devices adapted to act on the body or limbs of a person, and preferably arranged to support all or a portion of the weight of the person to be treated, or to receive pressure from the person, with means for supporting and actuating such rollers or massage devices.

40 In the form of construction shown in the drawings, 3 represents a base having stands or bearings 4 at one end thereof, which are bored to receive trunnions 5 from brackets 6, which in turn carry a rectangular frame

45 7. The trunnions are bored to receive a driving shaft 8, which may be driven in any desired manner, as by means of a pulley 9, which is connected by a belt 10 with a pulley 11 on a motor 12. The driving shaft 8

50 is provided with sprockets 13 and 14 which are arranged in alinement with sprockets 15 and 16 on a shaft 17, which shaft is adjustably mounted in bearings in brackets 18, which brackets are secured to the sides of

55 the frame 7. This adjustment may be made in any convenient manner, as by having the

bearings for the shaft 17 slidably mounted in elongated openings in the brackets, and held in position by set screws 19. These sprocket wheels carry chains 20 and 21, 60 which are arranged at either side of the frame, and these chains carry the rollers 22. The rollers or massage devices may be supported in any convenient manner, as by means of brackets 23, which are connected 65 directly to the chains, and have rods or shafts 24 extending longitudinally thereof, and supported in the ends of the brackets, which rods carry the rollers 22. These rollers or massage devices may be made of 70 any suitable material and may be made in sections or of such configuration as may be desired. These are the elements which act upon the person to be treated, and they are preferably made sufficiently long so that 75 they will make contact with the full width of the back and shoulders, and also the rear portions of the arms of a person lying thereon or pressing against the same. A seat 25 is carried on brackets 26, which 80 brackets are adjustably mounted on the frame 7 and are held in position by means of set screws 27 or the like. A foot rest 28 is hinged to the outer edge of the seat 25 so that it may be swung up into alinement 85 with the seat, or may be swung down to the position indicated at Fig. 1. Supporting rods or braces 29 are hinged at 30 to the brackets 26, and the outer ends of these rods are provided with screws or bolts 31 to engage with holes 32 in the foot piece 28 for holding it in position. A head piece or head rest 33 is secured to the upper end of the frame, and serves as a support for the head as well as to prevent the hair from 90 being engaged by the rollers. In order to adjust the frame to different positions, adjustable brackets 34 and 35 are secured to the sides of the frame, as by means of set screws, and a yoke 36 is pivoted to these 95 brackets. This yoke is provided with a threaded stem or rod 37, which engages with a tube 38, which tube is pivoted at 39 to the base 3. A hand wheel 40 with a threaded nut engages with the rod 37 and 100 upper end of the tube 38, and provides means for moving the rod up and down.

The chains and supports are preferably made sufficiently strong so that no additional supports are needed, whereby the upper flights of the chains will give a yielding action to the rollers. As indicated by 110

the dotted figure in Fig. 1, the preferred method of using this machine is for the person to seat himself on the seat 25 with the back resting upon the rollers 22. The 5 pressure may be increased or decreased to a certain degree by raising or lowering the movable end of the frame. The pressure may also be controlled to a certain degree by the person being treated, depending 10 upon the manner in which they hold themselves on the seat and against the head rest. If it is desired to increase the pressure, this may be done by the person pressing against a cross bar 41, which is supported in arms 15 42 extending out from the brackets 34 and 35. Likewise the foot rest 28 may be swung up more or less in alinement with the seat 25 so that the person can push against this support and thereby push themselves 20 against the rollers. While the chains may be reciprocated or driven in either direction, they are preferably driven so that the engaging rollers will be descending, or driven in the direction indicated by the arrow 25 in Fig. 1.

The operation of this improved body treatment or massage device will be obvious from the drawings. The motor being started will drive the driving shaft, which in 30 turn will drive the chains and thereby carry the rollers around in the direction desired. The patient sits upon the seat 25 with the back, the rear portion of the neck, back of the arms, and such other portions of the 35 anatomy as may be conveniently brought into engagement with the rollers, or massage devices resting thereupon. These rollers are preferably made of wood, and serve to give an exceedingly efficient and thorough massaging action to the portions of the body coming in contact therewith. The person treated may assist the operation to a certain extent by pressing on the cross bar 41 or foot support 28 if desired. The 40 seat may be readily adjusted for the convenience of different sized persons, and the position of the frame may be readily adjusted to increase the pressure, or to bring the person into such position as will be most agreeable for the treatment. It is readily 45 apparent that various changes may be made in the structure of this apparatus, and in the construction and arrangement of the details without departing from the scope of this invention, and therefore I do not wish to be limited to the exact form or arrangement shown, except as specified in the following claims, in which I claim:

1. In a massage machine, the combination 50 of a pair of belts arranged side by side, a plurality of horizontally arranged massage devices carried by said belts and adapted to engage with the body of a person, the portions of said belts carrying the 55 devices in active engagement with the body

being arranged to travel in paths inclined to the perpendicular, and means for actuating said belts to cause the devices to move while in contact with the body.

2. In a machine of the character set forth, 70 the combination of a frame, shafts mounted on said frame, means for turning one of said shafts, endless belts carried by said shafts, body engaging devices carried by said belts and arranged horizontally, and means connected with said frame for partially supporting a person thereon, to permit portions of the body of the person to engage with said body engaging devices.

3. In a machine of the character set forth, 80 the combination of a frame, means for adjusting said frame to change the angle thereof in a vertical plane, a horizontal driving shaft at the lower end of the frame, a driven shaft at the upper end of the 85 frame, sprockets on said shafts, chains carried by said sprockets, horizontally arranged rollers carried by said chains, a seat on said frame, and a head rest at the upper end of the frame, the arrangement being 90 such that the body of a person sitting on the seat may come in contact with the rollers between the seat and the head rest.

4. In a machine of the character set forth, the combination of a base, a frame pivotally 95 mounted on said base, means for supporting and adjusting the free end of the frame, a driving shaft at the lower end of the frame, means for driving said shaft, a second shaft at the upper end of the frame, sprocket 100 wheels carried by said shafts, chains passing over said wheels, brackets connecting between said chains, a continuous series of rollers carried by said brackets, an adjustable seat at the lower end of the frame, and a head rest at the upper end of the frame, the parts being arranged to expose the rollers between the head rest and the seat, whereby a person on the seat may bring his back or other portions of the body into 105 engagement with said rollers.

5. In a machine of the character set forth, the combination with a continuous series of movable body engaging devices adapted to support all or a portion of the weight of a 115 person, of abutments arranged adjacent to said devices whereby the person may press against said abutments to increase the pressure against the devices.

6. In a machine of the character set forth, 120 the combination of a base, bearings on said base, a frame having trunnions engaging with said bearings, a shaft carried by said trunnions, a motor for driving said shaft, an adjustable shaft mounted at the free end 125 of the frame, sprockets on said shafts, chains passing over said sprockets, rollers carried by said chains, an adjustable support connecting between the free end of the frame and the base, a head rest at the upper 130

end of the frame, an adjustable seat at the lower end of the frame, and abutments arranged at a convenient distance in front or above the frame, against which the person 5 may press to increase the pressure on the rollers.

7. In a body treatment machine, the combination of a pivotally mounted frame, adjustable supporting means for swinging the 10 frame from a substantially horizontal posi-

tion to a raised position, belts mounted in said frame, a plurality of horizontally arranged massage devices carried by said belts and adapted to engage with the body of a person, and means for driving said belts. 15
